UNITED STATES PATENT OFFICE

EDWIN W. STROM, OF WOBURN, MASSACHUSETTS, ASSIGNOR OF ONE-HALF TO PAUL BILEZIKIAN, OF WATERTOWN, MASSACHUSETTS, AND ONE-HALF TO ARAKEL S. BILEZIKIAN, OF NEWTON, MASSACHUSETTS

STEAM GENERATOR

Application filed March 13, 1928. Serial No. 261,321.

This invention relates to a steam generator outfit designed for the use of tailors and pressers and has for its primary object the provision, in a manner as hereinafter set forth, of means for generating a working pressure of steam quickly and for maintaining the working pressure during the entire period in which the pressing machine with which it is connected, is in operation.

10 The present outfit is designed to receive approximately three gallons of water which is heated at the rate of about two and one half pounds per minute raising the temperature from forty degrees to the boiling point 15 in approximately twelve minutes and reaches a working pressure of fifty pounds, in approximately forty minutes. Means are provided for regulating pressure at any desired point. With similar devices at present 20 in use there is a great loss of heat and these devices do not heat faster than one pound of water per minute taking approximately one and one-half hour to heat to a proper working pressure. It has been found

25 that heating boilers of the type to which this present boiler relates do not maintain the steam pressure constant and at the proper working temperature when the device is in use. The present structure is designed to 30 overcome these difficulties through the use and connection of the apparatus hereinafter described.

The invention will be best understood from a consideration of the following detailed description taken in connection with the accompanying drawing forming a part of this specification, with the understanding, however, that the invention is not confined to any strict conformity with the showing 40 of the drawing but may be changed or modified so long as such changes or modifications mark no material departure from the salient features of the invention as expressed in the appended claim.

45 In the drawing:

Figure 1 shows the steam generating outfit embodying the present invention, set up for use.

50 Figure 2 is a central longitudinal sec-

tion through the lower portion of the boiler showing the heating units therein.

Figure 3 is a bottom plan view of the boiler showing the arrangement of the heating unit.

55 Figure 4 is a view taken substantially upon the line 4—4 of Figure 1.

Referring now to the drawing in detail, wherein like numerals of reference indicate corresponding parts throughout the several views, the numeral 1 indicates a steam boiler of an appropriate design, designed to contain approximately three gallons of water. The lower end of the boiler 1 is closed by the electric unit carrying plate 2, the electric units supported thereby being indicated by the numerals 3. Each of these units 3 is threadably engaged in the plate 2 in the manner shown and have their heating coils 4 extending upwardly into the boiler 1. 70 These coils are of the usual insulated type, each being a standard electric immersion heater drawing approximately two kilowatts of current.

75 Adjacent its lower end the boiler body 1 is provided with a pair of nipples 5 and 6 into one of which as for example the nipple 5, a water supply pipe 7 leads, this pipe being controlled by a valve 8. Into the other nipple there leads a steam return pipe which is 80 connected to the machine in connection with which the generating outfit is used, this pipe being indicated by the numeral 9 and having a one way or trap valve 10 therein.

85 At approximately the central portion of the boiler 1 is located a water gauge 11 having the usual cut-off valve 12 at each end, which gauge is employed to indicate the height of the water in the tank.

In addition to the gauge 11 the boiler is 90 provided with a series of try cocks 13 which are arranged in different planes as shown in Figure 1 and by means of which the height of the water in the boiler can be determined.

The top of the boiler 1 is provided with a blow-off or safety 14, a steam pressure indicator 15 and a steam lead-off pipe 16 which conveys steam to the machine for use.

95 Current is supplied to the immersion heaters 3 through the line 17 which leads from

a magnetically controlled switch 18 which may be of any appropriate make. This magnetic switch 18 is supplied through the line 19 which in turn is controlled by a main control switch 20.

5 The current supply to the heaters 3 is regulated by means of a pressure switch 21 which switch like the magnetic switch 18 may be of any desired construction, this pressure switch 10 having the electric current line 22 leading therefrom to the magnetic switch.

15 Leading from the boiler 1 is a pipe line 23 which goes through the magnetic switch and through which the water pressure within the boiler is transmitted so that when the pressure reaches a predetermined point the pressure switch will operate to actuate the magnetic switch which in turn will open or close the circuit to the immersion heaters in accordance with the boiler pressure.

20 The boiler structure is preferably coated or covered with a suitable heavy insulation material 24 which acts to prevent the loss of heat into the surrounding atmosphere.

25 As is clearly shown in Figure 2 the plate 2 which carries the immersion heaters 3 is substantially pan-shaped and receives in the surrounding inside groove 25 the lower edge of the boiler body 1. To this plate there is secured suitable supporting legs 26 which support the boiler structure. A draw-off 27 is provided which opens through the plate 2 in the manner clearly shown in Figure 2.

30 From the foregoing description it will be readily seen that upon closing the switch 20 which controls the main supply line of the current the immersion heaters will become energized and these heaters are designed to heat the contents of the boiler to a working pressure and maintain this pressure as long as steam formed therein is being used. In the event that the pressure becomes excessive it will be transmitted through the pipe line 23 to the pressure switch 21 which switch 40 will operate to actuate the magnetic switch 18 which in turn will break the current supply to the heaters and thus permit the boiler to cool down until the pressure therein has returned to normal.

45 50 From the foregoing description it will be readily seen that there has been provided a compact and efficient steam generating system which is serviceable and comparatively inexpensive to set up.

55 Having thus described my invention what I claim is:

60 In a steam generating outfit, a boiler including a body having a cylindrical side wall, the lower end of said body being open, a deep pan shaped plate constituting a head for the open end of the boiler and including a flat lower wall and a cylindrical side wall, the side wall of the plate being provided with an annular seat adjacent to its upper edge for 65 the reception of the lower end of the cylindri-

cal side wall of the body, and a plurality of electric immersion heaters carried directly by the lower wall of said plate and extending into the body, as and for the purpose specified.

70 In testimony whereof I affix my signature.
EDWIN W. STROM.
